UNITED STATES PATENT OFFICE.

ARTHUR J. MILLER, OF WARREN, PENNSYLVANIA.

CAMERA.

1,344,182.

Specification of Letters Patent. Patented June 22, 1920.

Application filed January 25, 1918. Serial No. 213,754.

To all whom it may concern:

Be it known that I, ARTHUR J. MILLER, a citizen of the United States, residing at Warren, in the county of Warren and State 5 of Pennsylvania, have invented a new and useful Camera, of which the following is a specification.

The present invention appertains to cameras, and aims to provide a novel and improved means for transferring sensitized 10 elements in a camera.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within 15 the scope of what is claimed, without departing from the spirit of the invention.

The invention is illustrated in the accompanying drawings, wherein:

Figure 1 is a side elevation of the improved camera, with the side doors and focusing windows in open position.

Fig. 2 is an enlarged vertical longitudinal section, the view being a median section from the back of the case or box to the rear portions of the bellows, portions being broken away, showing one plate holder lowered and moved back.

Fig. 3 is an enlarged cross section showing the forward surface of the back, the side doors being shown in section.

Fig. 4 is an enlarged fragmental cross section looking forwardly and showing the shifting device.

Fig. 5 is a horizontal section taken on the line 5—5 of Fig. 2.

Fig. 6 is a perspective view of the rod for shifting the plate or film holders, a portion thereof being broken away.

In carrying out the invention, the body 45 or frame of the camera comprises a rectangular case or box 1 of suitable size and material, which will be described as being upright, although it can be used in other positions. This case 1 is provided between its upper and lower ends and adjacent the front thereof with a horizontal partition 2 separating the upper and lower camera sections, and said case is provided therein above and 50 below the partition 2 with cleats 3 to which the rear ends of the upper and lower bellows

4 and 5, respectively, are attached. The forward ends of said bellows are attached to the respective upper and lower standards or supports 6 and 7 for the lenses L and 60 their shutters, and said standards 6 and 7 are arranged to slide forwardly onto the front doors or beds 8 and 9, respectively, when they are swung forwardly and downwardly to horizontal position, as seen in 65 Fig. 1. These doors 8—9 are hingedly connected with the case 1 and when swung upwardly and rearwardly close the front of the case, and can be held in closed position in any suitable manner. The standards 6—7 70 are slidable in the usual fashion upon the doors 8—9, and are movable into the case 1 when the camera is folded, to enable the doors 8—9 to be closed. The shutters of lenses L can be operated simultaneously by 75 any desired means R. The case 1 is provided therein adjacent the back thereof and in rear of the upper and lower camera sections, with the magazine chamber 10 and combined 80 magazine and transferring chamber 11, adjacent the upper and lower ends of the case, respectively, and separated by a partition or shelf 12 of sheet metal or other suitable material disposed horizontally in rear of the partition 2. The back 13 of the case is removable, the same being attached to the rear edges of the sides and ends of the case by screws 14 or other suitable securing means. The back 13 is provided in rear of 85 the chambers 10 and 11 with suitable light-tight spring-actuated focusing windows 15 and 16 of any suitable size.

One side, preferably the right side, of the case 1 is provided with an opening 27 extending from the top of the case to the bottom thereof and located adjacent the back 13, and upper and lower doors 28 and 29, respectively, are hinged to the back 13, forming a light-tight joint with the back 13 and 90 with the adjacent edges of the case to close the opening 27. The doors 28—29 can be held closed by latches 30 carried by the case 1.

Movable backwardly and forwardly within the chambers 10 and 11 are holders 33 for the sensitized plates, negatives, or the like. Each of the holders 33 embodies a backing 34 constructed of suitable opaque material having its margin attached in any suitable manner to the rear side of a rectangular frame 35.

The chamber 10 is adapted to receive a plurality of the holders 33 one behind the other, with the partition 12 supporting said holders, and the chamber 11 is also adapted 5 to accommodate said holders for backward and forward movement. The right hand ends of the holders 33 are provided with consecutive numerals or indexes 44, visible through windows 44' in the doors 28-29, 10 and the ends of the holders are further provided with finger holds 45 to facilitate the insertion and removal of said holders. The upper edges of the holders 33 are provided with forwardly facing bevels 46, while the 15 lower edges thereof have rearwardly facing bevels 47, to facilitate the movement of the holders from one chamber to the other of the case 1. The upper pieces or edges of the holders 33 are provided midway between the 20 ends thereof with sockets or recesses 48, and the lower pieces or edges of the holders are provided midway between the ends thereof with similar sockets or recesses 49.

The forward edge of the partition 12 is 25 spaced slightly from the rear edge of the partition 2, to define a transverse slot 51 (Fig. 2) through which the holders 33 are movable downwardly from the forward portion of the chamber 10 into the forward portion 30 of the chamber 11, and the rear edge of the partition 12 is spaced from a cleat 54 at the back 13 to provide a transverse slot 51' through which the holders 33 are movable upwardly from the rear portion of the 35 chamber 11 into the rear portion of the chamber 10, thus providing for the circuitous movement of the plate holders. In order to normally close the slots 51-51', to prevent the passage of light between the 40 chambers 10-11, a shutter 52, constructed of sheet metal or other suitable material, is connected by any suitable spring hinge to the forward edge of the partition or shelf 12 and swings up into alignment with the 45 partition 2, and a similar shutter 53 is hinged to the cleat 54 to swing down and close the slot 51'. That end of the partition 12 opposite to the opening 27 is bent and secured as at 426 in any suitable manner 50 to the corresponding side wall of the casing and the other end is supported by a rod 55 carried by the casing and extending across the door opening 27. The partition 12 and rod 55 extend between the doors 28- 55 29 to prevent light escaping past the partition. The shutters 52 and 53 can readily swing open downwardly and upwardly when the holders 33 are moved past them, and swing shut automatically when the holders 60 have passed.

The case 1 is provided at the forward portions of the chambers 10 and 11 with cleats or shoulders 50 providing stops against which the holders 33 are adapted to bear by 65 a forward movement, and along which the

holders are slidable downwardly from the chamber 10 into the chamber 11.

Disposed within the chamber 11 is a focusing screen 70 carried by a frame 69 having an upper reverse bevel 125, said screen being 70 preferably constructed of celluloid, which is light and strong, so as not to be easily breakable nor heavy as glass, although any suitable screen is used. A similar screen 70' having a frame 69' is provided within the 75 chamber 10 in rear of the holders 33.

As a means for moving the holders 33 and the screens forwardly in the chambers 10-11, presser or follower members 71 and 72 are carried by the back 13 in rear of the 80 respective chambers 10 and 11, and said members are of practically duplicate construction, each being of U-shape, and being accommodated and receivable in a U-shaped recess 73 with which the back is provided. The intermediate portion of each of said follower members is mounted for rotation in bearings 74 carried by the back 13, and springs 75 connect each follower member and the back so as to tend to swing the arms 90 of said member forwardly. The follower members can be held in inoperative positions within the recesses 73 by means of latches 76' carried by the back 13, but when the latches are released, the members 71 and 72 95 swing forwardly, and the ends of their arms bear against the side portions of the rear-most holders 33 against the frames 69-69' of the screens. Thus, the follower members in swinging forwardly press, when free to 100 do so, the foremost carriers 33 or the screens or against the cleats or stops 50. Suitable slots 76" are provided in the rear surfaces of upright screen frames 69-69' in which the free ends of the follower members 71-72 105 move, thereby holding the screens securely against transverse movement while withdrawing plate or film holders from chambers. The follower member 72 is provided with a lever 17 within a recess 18 in the case 110 to retract or manually move the member 72, the lever 17 being held by a ratchet 19.

The device for transferring the holders or carriers 33 within the chamber 11, embodies an inverted U-shaped follower member 76 carried for oscillatory movement by the cleat 50 of the chamber 11 and movable out of the way into a groove 77 in the said cleat 50. Springs 78 tend to swing the arms of the member 76 rearwardly, and said member has an operating lever 79 extending through a slot 80 in a segment plate 81 set in a recess 82 in the case, in which recess the lever or arm 79 works. The segment plate 81 and the lever 79 have suitable co-operating elements 83 for holding the lever 79, with the member 76 retracted or moved rearwardly. When a holder 33 is moved downwardly through the slot 51, the holder passes in front of the screen frame 69 behind 130

the follower 76, and is pressed by the screen frame 69 against the cleat 50 in the chamber 11 due to the pressure of the follower 72 against the screen frame. After exposure of the plate in holder 33, the follower member 72 is retracted by the lever 17, and the member 76 is then released by the lever 79. The springs 78 then move the member 76 rearwardly, pushing the holder 33 and frame 69 ahead of member 76 until the frame 69 moves to rest against the back 13. This operation retains the plate holder 33 in position to be moved up through the slot 51'. Then by retracting the member 76 and releasing the member 72 the screen frame 69 is again brought against the cleat 50 in the chamber 11.

In order to facilitate the movement of the holders 33 from one chamber to the other, the bottom or lower end of the case 1 has an apertured guide member 89 below the slot 51', and adjacent the back 13, and the top or upper end of the case has a similar apertured guide member 90 above the slot 51 adjacent the forward portion of the chamber 10. The apertures of the members 89-90 are normally closed by inner flaps or closures 92-91, respectively, which normally swing to closed position, but which are yieldable so as to be swung out of the way by a rod 93 insertible into the guide members. This rod 93 is provided at one end with a knob or finger piece 94 to facilitate the manipulation of the rod. When the rod 93 is inserted through the upper guide member 90, the foremost holder 33 in the chamber 10 can be pushed downwardly into the chamber 11, and when the rod 93 is inserted through the lower guide member 89 with the holder 33 within the chamber 11 moved rearwardly, said holder can be moved upwardly back into the chamber 10.

The camera may include a swing-back mechanism 95, a register 105, means 116 for focusing, and other adjuncts forming no part of this application so far as the claims are concerned.

In preparing the camera for taking a series of pictures, a "stack" of holders 33 containing sensitized plates are deposited in the magazine chamber 10, this of course being done under a ruby light or in a dark room, and the screen 70' is disposed in the chamber 10 in rear of the holders 33. Screen 70 is moved by the follower member 72 to the normal focusing plane, which will be subsequently occupied by the sensitized surface of the plate contained in the first holder 33 in magazine 10. Then, by opening the lower focusing window, the proper focus can be obtained, by adjusting the lower lens. After the lower window is closed, the rod 93 is inserted through the guide member 90 and is pushed downwardly, the lower end of said rod engaging the upper recess 48 of the

foremost holder 33, whereby said holder will be forced downwardly by the rod 93 through the slot 51 along the cleats 50, the shutter 52 opening automatically. In this manner, the foremost holder 33 in the magazine chamber 10 is slid downwardly into the chamber 11, and when said holder is moved downwardly, the lower bevel 47 thereof engages the upper reverse bevel 125 of the screen frame 69, whereby the holder 33 wedges between the screen frame 69 and the cleats 50 and member 76, forcing said frame 69 rearwardly against the forward tension of the arms 78. Consequently, the holder is moved between the cleats 50 and frame 69, the focusing screen 70 being moved rearwardly from the focus plane, and the sensitized surface of the holder 33 being moved into the position previously occupied by the screen 70'. After the exposure has been made, the "exposed" holder 33 can be transferred back into the magazine chamber 10 at the rear of the "unexposed" holders 33 or in the rear of the screen 70'. This is accomplished by releasing the member 76 as above described. When the frame 69 is moved rearwardly against the back 13, the "exposed" holder 33 is in position to be moved back upwardly into the chamber 10. The rod 93 which was previously withdrawn from the guide member 90 after the holder was moved downwardly into the chamber 11, as above described, is now inserted upwardly through the guide member 89, the end of the rod 93 engaging the lower recess 49 of the "exposed" holder, and when said rod is moved upwardly, the holder will be forced from the chamber 11 back up into the chamber 10, the shutter 53 opening automatically, whereby to permit the holder to move through the slot 51'. When the holder is returned to the chamber 10, it wedges between the follower member 71 and the screen frame 69' or rearmost holder 33 and when the "exposed" holder is moved completely into the chamber 10, the follower member 71 moves it forwardly onto the partition 12. When the next subject is to be photographed, the new focus can be obtained, the screen 70 being returned to focusing position, for a new operation, which is carried out the same as before.

Having thus described the invention, what is claimed as new is:

1. A camera having a magazine chamber 120 and a transferring chamber, camera sections for the two chambers, a focusing screen in the transferring chamber movable into and out of focusing position, and a plurality of holders for sensitized members 125 within the magazine chamber, the foremost holder being in focusing position and being movable into focusing position in the transferring chamber.

2. A camera embodying a case having 130

magazine and transferring chambers and a partition between said chambers, a camera section for one of said chambers in front thereof, a plurality of holders 5 for sensitized members in the magazine chamber, the foremost holder being movable from the magazine chamber into the transferring chamber, and means operable within the transferring chamber for 10 moving the holder rearwardly, the holder when moved rearwardly within the transferring chamber being movable back into the magazine chamber.

3. A camera embodying a case having 15 magazine and transferring chambers and a partition between said chambers, a camera section for one of said chambers in front thereof, a plurality of holders for sensitized members in the magazine chamber, the foremost holder being movable from the magazine chamber into the transferring chamber, means operable within the transferring chamber for moving the holder rearwardly, the holder when moved rearwardly within 20 the transferring chamber being movable back into the magazine chamber, and means for moving the holders from each chamber 25 into the other.

4. A camera embodying a case having 30 magazine and transferring chambers and a partition between said chambers, a camera section for one of said chambers in front thereof, a plurality of holders for sensitized members in the magazine chamber, the foremost holder being movable from the magazine chamber into the transferring chamber, means operable within the transferring chamber for moving the holder rearwardly, the holder when moved rearwardly within 35 the transferring chamber being movable back into the magazine chamber, and a rod insertible into the case for pushing the 40 holders from one chamber into the other.

5. A camera embodying a case having a 45 magazine chamber and a transferring chamber, and a partition between said chambers, a camera section for one chamber, there being slots at the forward and rear edges of said partition, holders for sensitized 50 members in the magazine chamber, the foremost holder in the magazine chamber being movable through the forward slot into the transferring chamber, and the holder when moved rearwardly in the transferring chamber being movable through the rear slot back into the magazine chamber, and means for closing said slots.

6. A camera embodying a case having magazine and transferring chambers and a

partition therebetween, a camera section for 60 the transferring chamber, a focusing screen in the transferring chamber, a plurality of holders for sensitized members in the magazine chamber, the foremost holder in the magazine chamber being movable into the 65 transferring chamber and when moved rearwardly in the transferring chamber being movable back into the magazine chamber.

7. A camera embodying a case having 70 magazine and transferring chambers and a partition therebetween, a camera section for 75 the transferring chamber, a focusing screen movable in the transferring chamber, a plurality of holders for sensitized members in the magazine chamber, the foremost holder being movable from the magazine chamber into the transferring chamber, said holders and focusing screen having coöperable bevels whereby a holder when moved into the transferring chamber will move in front of the focusing screen, means operable within the transferring chamber for moving the focusing screen and holder rearwardly therein, the holder when moved rearwardly 80 in the transferring chamber being movable 85 back into the magazine chamber.

8. A camera embodying a case having 90 magazine and transferring chambers and a partition therebetween, a camera section for 95 the transferring chamber, a focusing screen movable forwardly and rearwardly in the transferring chamber, a plurality of holders for sensitized members in the magazine chamber, the foremost holder in the magazine chamber being movable into the transferring chamber, the holder when moved rearwardly in the transferring chamber being movable back into the magazine chamber, and a manually operable rock shaft carried by the case in front of said 100 transferring chamber and having arms whose free ends are engageable with the focusing screen and holder in front of the same, respectively, whereby said arms can be swung for moving the screen and holder 105 rearwardly, the holders and screen having coöperable means whereby a holder when moved from the magazine chamber into the transferring chamber will move in front of the focusing screen and in rear of said arms. 110

In testimony that I claim the foregoing as my own, I have hereto affixed my signature in the presence of two witnesses.
